FEED REGULATING MEANS FOR SEWING MACHINES

Frank Parry, Bridgeport, Conn., assignor to The Singer Manufacturing Company, Elizabeth, N. J., a corporation of New Jersey

Application June 12, 1945, Serial No. 599,059

10 Claims. (Cl. 112—210)

This invention relates to sewing machines and more particularly to sewing machines of the type embodying a compound work-feeding mechanism. As is well understood in the art, a compound work-feeding mechanism comprises a reciprocating feed-dog located beneath the work, and engaging the under side thereof, and a thread-carrying needle located above the work and having a reciprocatory motion to cause it to penetrate the work and also a vibratory motion while in the work to cause it to advance the work synchronously with the work-advancing movement of the feed-dog.

To adapt compound feed machines for various operations on different types of materials, it is essential that means be provided for varying the feeding strokes of both the upper and lower work-feeding elements, thereby to vary the length of the stitches produced.

It will readily be perceived that with a construction of this nature it is important that the feeding stroke of the needle and the feeding stroke of the feed-dog be of precisely the same amplitude, otherwise damage to either the work or the needle will result.

This invention has as its primary object to provide improved means for simultaneously and synchronously adjusting the actuating elements for both the upper and lower feeds of a compound feed sewing machine.

Another object of the invention is to provide improved means by which the operator may, with one hand and by a single manipulation of one element, simultaneously lock one portion of the feed-drive eccentrics of both the upper and the lower feed mechanisms, whereby actuation of another element by the other hand of the operator will effect simultaneous and synchronous adjustment of both eccentrics.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

In the drawings,

Fig. 1 is a longitudinal sectional view of a sewing machine embodying the present invention.

Fig. 2 is a vertical section taken substantially on the line 2—2 of Fig. 1.

2

Fig. 3 is a vertical section taken substantially on the line 3—3 of Fig. 1.

Fig. 4 is a bottom view of the machine shown in Fig. 1.

Fig. 5 is a detail sectional view illustrating improved means for pivotally mounting in the bracket-arm head an oscillatory needle-bar frame later to be described.

Fig. 6 is a perspective view of an adjusting screw later to be described.

10 Referring more specifically to the drawings, the invention is disclosed as embodied in a sewing machine having a frame including a work-supporting cloth-plate or bed 1 and a bracket-arm secured to the bed and comprising a standard 2 and an overhanging arm 3, supporting at its free end a bracket-arm head 4. Journaled in anti-friction bearings 5 and 6, and disposed lengthwise within the arm 3, is a main or needle-bar actuating shaft 7, carrying, at its rear end, 15 a combined belt and hand wheel 8 having a V-shaped annular groove 9 adapted to receive a driving belt by means of which the shaft may be rotated from any suitable source of power.

Secured upon the shaft 7, adjacent its rear end, is a grooved pulley 10 which through a clip-belt 11 drives, in one-to-one ratio, a similar pulley 12 fixed upon a lower rotary shaft 13. The shaft 13 is journaled in bearings 14, 15 and 16 which are respectively carried by lugs 17, 18 and 19 formed integral with and depending from the under side of the bed 1.

Within the bracket-arm head 4 there is mounted, for oscillation, a needle-bar frame 20 having upper and lower arms 21 and 22 in which is reciprocably mounted a needle-bar 23, carrying, at its lower end a pair of eye-pointed needles n. The needle-bar is reciprocated in its bearings in the arms 21 and 22 by a link 24, connected, at 40 one end to a collar 25 on the needle-bar and at its other end to a crank pin 26 carried by a crank disk 27 secured to the forward end of the shaft 7. Thus rotation of the shaft 7 effects endwise reciprocation of the needle-bar and the needles carried thereby.

Mounted for vertical reciprocation in a tubular bearing b secured in the bracket-arm head 4, is a spring-depressed presser-bar c which carries, at its lower end, a presser-foot d. This presser-foot is adapted to hold the work on a throat-plate p, supported by the cloth-plate 1, and to cooperate with a serrated feed-dog, located beneath the throat-plate, in the feeding of the work.

55 Cooperating with the needles, in the forma-

tion of stitches, are two rotary loop-takers *t* located beneath the cloth-plate 1 and each driven at a two-to-one ratio from the shaft 13 by gears 28, 29.

The needle-bar frame 20 is secured to a rock-shaft 30 journaled in anti-friction bearings 31 and 32 fitted in bosses 33 and 34 in the lower end of the bracket-arm head. The bearing boss 33 carries a wear-plate 35 against which abuts the lower arm 22 of the needle-bar frame. That end of the shaft 30 within the bearing 32 is provided with a bore 36 into which is threaded a screw 37 having its head 38 fitted within a counterbore 39 in the bracket-arm head and bearing against a spring washer 40 in said counterbore. The screw 37 is split, as shown at 41 in Fig. 6, and is provided with an axial bore 42 into which is threaded the body portion of an expansion plug 43 having a tapered point 44 engaging the reduced inner end of the bore 42. By turning the screw 37, the parts may be drawn into proper working relation with each other, after which the parts may be locked in that position by screwing inwardly the plug 43, whereupon the tapered point 44 causes the screw 37 to expand, thus locking the screw against accidentally turning.

The needle-bar frame 20 is oscillated about the longitudinal axis of the rock-shaft 30, thereby to give to the needles *n* feed and return movements in timed relation with the movements of the usual lower feeding mechanism hereinafter to be described, by means of connections comprising a rock-lever 45 formed with a split lower end adapted to be clamped by a screw 46 to the rock-shaft 30. The upper end of the rock-lever 45 is operatively connected to one end of a pitman 47, the other end of which is formed as a strap 48 which surrounds an eccentric 49 forming a part of an adjustable eccentric device, designated generally as *E*, secured upon the arm shaft 7. It will be understood that as the arm shaft is rotated, the eccentric 49 actuates the pitman 47, which in turn operates the rock-lever 45 to oscillate the needle-bar frame 20 about the axis of the rock-shaft 30. The extent of oscillatory motion imparted to the needle-bar frame, and thereby the amplitude of feeding motion transmitted to the needles is dependent upon the amount of eccentricity of the eccentric 49. In order to vary the amplitude of the oscillatory movements of the needle-bar frame to harmonize the same with the stitch length to which the lower feeding mechanism is adjusted, the eccentric device *E* is so constructed that the eccentricity of the eccentric 49 may be adjusted between certain limits. Inasmuch as the details of construction of this adjustable eccentric device forms no part of the present invention, and furthermore as the same is completely disclosed in the United States patent of Myers, No. 2,128,031, dated August 23, 1938, of detailed illustration and description thereof in this specification is deemed unnecessary.

Suffice it to say that adjustment of the eccentric 49 is effected by relative rotation between the member 139 of the adjustable eccentric device and the arm shaft 7.

Below the cloth-plate 1, the machine is provided with a four-motioned lower feeding mechanism including a feed-dog 50, carried by a feed-bar 51 having a fork 52 engaging a feed-lift eccentric 53 secured upon the shaft 13. At its forward end, the feed-bar is pivotally connected to a feed-rocker 54 secured upon a feed-drive rock-shaft 55 journaled in bearings 56 supported in bearing bosses 57 formed integral with the bed-plate 1.

Upon one end of the shaft 55, there is secured a rock-arm 58 pivotally connected at 59 to one end of a pitman 60, the other end of which is formed as a strap 61 surrounding a lower feed-drive eccentric 62 forming a part of a second adjustable eccentric device *E'* secured upon the shaft 13. Thus rotation of the shaft 13 and the eccentrics 53 and 62 thereon, effects rising-and-falling and feed-and-return movements of the feed-bar 51 and the feed-dog 50 carried thereby. The construction of the adjustable eccentric device *E'* on the shaft 13, is the same as that carried by the arm shaft 7 which, as above stated, is fully disclosed in United States Patent No. 2,128,031 and includes a member 139' which is rotatable relative to its supporting shaft 13 to vary the eccentricity of the eccentric 62.

As illustrated in the drawings, the machine also includes means for providing a thread-clearance space between the nose of a thread-carrier, (not shown) forming a part of each of the loop-takers *t*, and stop-lugs (not shown) provided by a throat-plate *p* supported by the bed 1. This mechanism forms no part of the present invention and therefore detail illustration and description thereof is deemed unnecessary for this disclosure. Portions of the mechanism, however, are designated generally as *x*.

As hereinbefore indicated, this invention relates primarily to improved means for simultaneously and synchronously varying the eccentricity of the upper feed-drive eccentric 49 and the lower feed-drive eccentric 62. This means comprises a manually oscillatable rock-shaft 63 journaled in bearings 64, 65 formed in the arm 3. Secured to the shaft 63, adjacent one end thereof and by a set screw 66, is the shank 67 of a hand-lever 68 which projects outwardly through an opening 69 formed in the forward wall of the standard 2 (see Fig. 3). The outer end of the lever 68 is flattened, as at 70, so as to be grasped conveniently between the thumb and finger of a user.

Secured upon the shaft 63, adjacent the bearing 64, is an arm 71 having an offset finger 72 adapted, upon turning of the shaft 63 in one direction, to enter an aperture or notch 73 formed in the periphery of the member 139 of the upper adjustable eccentric device *E*.

Intermediate its ends, the hand-lever 68 is pivotally connected, at 74, to the upper end of a vertically disposed link 75, located mainly within the machine standard 2. The lower end of the link 75 is pivotally connected, at 76, to the free end of a rock-arm 77 carried by one end of a rock-shaft 78 journaled, parallel with the shaft 63, in bearing bosses 79 depending from the cloth plate 1. Fixed to the other end portion of the rock-shaft 78, is an arm 80 having an offset finger 81 adapted, upon turning of the rock shaft in one direction, to enter an aperture or notch 73' in the periphery of the member 139' of the lower adjustable eccentric device *E'*.

The shaft 78 is normally biased in a counter-clockwise direction, as seen in Fig. 3, by a torsion spring 83 surrounding the shaft and having one end thereof secured to the shaft by a screw 84. The opposite end portion 85 of the spring projects laterally and bears against the under side 70 of the cloth-plate 1. This bias of the shaft 78 is transmitted to the shaft 63 by the rock-arm 77, link 75 and hand-lever 68. Thus the fingers 72 and 81 of the arms 71 and 80, respectively, are normally maintained out of engagement with the apertures 73 and 73' in the members 139 and 139'.

139' of the adjustable eccentric devices E and E'. When it is desired to vary the eccentricity of the eccentrics 49 and 62, the operator grasps the portion 70 of the lever 68 and swings the lever upwardly in the slot 69. This simultaneously turns the shafts 63 and 78 clockwise, as seen in Fig. 3 and places the fingers 72 and 81 in position to enter the notches 73 and 73', respectively. With the elements 139, 139' held against rotation by the fingers 72, 81, the operator grasps the hand-wheel 8 and turns the shaft 7, which through the pulleys 10 and 12 and clip-belt 11, simultaneously and synchronously turns the shaft 13. Angular movement of the shafts 7 and 13 relative to the members 139, 139' varies the eccentricity of the eccentrics 49 and 62, as fully described in the above mentioned Myers Patent No. 2,128,031. Turning of the shaft 7 in one direction increases the eccentricity of the eccentrics 49 and 62 and thereby increases the length of work-feeding movement transmitted to the needles n and feed-dog 50. Turning of the shaft in the opposite direction has the opposite effect.

From the foregoing it will be apparent that with this improved and simplified feed-adjusting mechanism an operator may easily, simultaneously and synchronously vary the feeding stroke of both the upper and lower work-feeding elements.

Having thus set forth the nature of the invention, what I claim herein is:

1. In a sewing machine having a frame including a work-supporting plate, a first work-feeding mechanism located beneath said plate, a second work-feeding mechanism located above said plate, individual means for regulating the feeding action of each of said feeding mechanisms, and a single manual control means for simultaneously and synchronously controlling the action of both of the feed regulating means.

2. In a sewing machine having a frame including a work-supporting plate, a first work-feeding mechanism located beneath said plate and including an adjustable feed-drive eccentric, a second work-feeding mechanism located above said plate and including an adjustable feed-drive eccentric, individual means for adjusting the feed-drive eccentric of each of said feeding mechanisms, and a single manual control means for simultaneously and synchronously controlling the action of both of the eccentric-adjusting means.

3. In a sewing machine having a frame including a work-supporting plate and a bracket-arm carried thereby having a head, a first work-feeding mechanism located beneath said plate, a second work-feeding mechanism carried by the bracket-arm adjacent said head, individual means adjacent each of said feeding mechanisms for regulating the feeding action thereof, and a single manual control means for simultaneously and synchronously controlling the action of both of the feed regulating means.

4. In a sewing machine having a frame including a work-supporting plate, a first work-feeding mechanism located beneath said plate and including a four-motioned feed-dog, a second work-feeding mechanism located above said plate and including an endwise reciprocable and laterally movable needle, individual means for regulating the feeding action of each of said feeding mechanisms, and a single control means including a manually shiftable lever for simultaneously and synchronously controlling the action of both of the feed regulating means.

5. In a sewing machine having a frame including a work-supporting plate and a bracket-arm carried thereby and having a head, a first work-feeding mechanism located beneath said plate, a second work-feeding mechanism carried by said bracket-arm adjacent said head, each of said feeding mechanisms comprising an adjustable eccentric device including relatively movable members, the relative movement of which varies 10 the action of the associated feeding mechanism, means including a rock-shaft journaled lengthwise of said frame beneath said work-supporting plate and an arm carried by said rock-shaft for locking one of the members of the eccentric device of the first feeding mechanism against movement, means including a second rock-shaft journaled lengthwise of said bracket-arm and an arm carried by said second rock-shaft for locking one 15 of the members of the eccentric device of the second feeding mechanism against movement, a single manually actuatable member connected to 20 simultaneously turn both of said rock-shafts and the arms carried thereby into member-locking position, and means thereafter to simultaneously and synchronously turn the other members of 25 said adjustable eccentric devices thereby to synchronously vary the action of both feeding mechanisms.

6. In a sewing machine having a frame including a work-supporting plate, a first work-feeding mechanism located beneath said plate and comprising an adjustable feed-drive eccentric device including an adjusting member having an aperture, a second work-feeding mechanism located 30 above said plate and comprising an adjustable feed-drive eccentric device including an adjusting member having an aperture, means for adjusting the feed-drive eccentric of each of said feeding mechanisms including two shafts journaled in said frame, a locking arm carried by each of said shafts and each having a portion designed 35 to enter one of said apertures, means to bias said shafts to a position in which said locking arms are out of locking engagement with said adjusting members, and manually actuatable means for moving said shafts in opposition to said biasing means to engage said locking arms with the apertures in said adjusting members.

7. In a sewing machine having a frame including a work-supporting plate, a first work-feeding mechanism located beneath said plate and comprising an adjustable feed-drive eccentric device including an adjusting member having a peripheral notch, a second work-feeding mechanism located above said plate and comprising an adjustable feed-drive eccentric device including an adjusting member having a peripheral notch, means for adjusting the feed-drive eccentric of each of said feeding mechanisms including two rock-shafts journaled in said frame, a locking arm carried by each of said rock-shafts and each having a portion designed to enter one of said notches, means including a torsion spring acting on one of said shafts to bias said shafts to a position in which said locking arms are out of locking engagement with said adjusting members, and a single manually actuatable means for turning said rock-shafts in opposition to said biasing means to engage said locking arms with the notches in said adjusting members.

8. In a sewing machine having a frame including a work-supporting plate, a first rotary shaft journaled in said frame above said plate, a second rotary shaft journaled in said frame beneath 75 said plate, first and second adjustable eccentrics

carried, respectively, by said first and second shafts, a lower work-feeding mechanism actuated from said second shaft and controlled by said second adjustable eccentric, an upper work-feeding mechanism actuated from said first shaft and controlled by said first adjustable eccentric, individual locking members cooperating with each of said adjustable eccentrics to vary the eccentricity thereof, and a single manually actuatable element operatively connected to actuate both 10 of said locking members.

9. In a sewing machine having a frame including a work-supporting plate, a first rotary shaft journaled in said frame above said plate, a second rotary shaft journaled in said frame beneath said plate, first and second adjustable eccentrics carried, respectively, by said first and second shafts, a lower work-feeding mechanism actuated from said second shaft and controlled by said second adjustable eccentric, an upper work-feeding mechanism actuated from said first shaft and controlled by said first adjustable eccentric, a 15 rock-shaft journaled in said frame adjacent and parallel to said first rotary shaft, a second rock-shaft journaled in said frame adjacent and parallel to said second rotary shaft, an operative connection between said rock-shafts, a locking member carried by each of said rock-shafts and each cooperating with one of said adjustable eccentrics to vary the eccentricity thereof, and 20 25 30

5 manual means for turning one of said rock-shafts thereby to render effective both of said locking members.

10. In a sewing machine having a frame including a work-supporting plate, a first rotary shaft journaled in said frame above said plate, a second rotary shaft journaled in said frame beneath said plate, a driving connection between said shafts, first and second adjustable eccentric devices carried, respectively, by said first and second shafts, each of said eccentric devices comprising a member normally rotated with its supporting shaft and an eccentric element associated with said member and adapted to be shifted relative thereto by relative angular movement between said member and its supporting shaft, thereby to vary the eccentricity of said eccentric element, an upper feeding mechanism actuated from said first shaft and controlled by said first adjustable eccentric device, a lower work-feeding mechanism actuated from said second shaft and controlled by said second adjustable eccentric device, and means controlled by a single manually actuatable element for locking both of said members against rotation whereupon turning of one of said shafts effects simultaneous and synchronous adjustment of both of said eccentric elements.

FRANK PARRY.
